AUGUST L. SCHULTZ, OF CLEVELAND, OHIO, ASSIGNOR TO MULTIGRAPH COMPANY, OF WILMINGTON, DELAWARE, A CORPORATION OF DELAWARE

PACKING MECHANISM FOR TYPESETTING MACHINES

Application filed August 24, 1931. Serial No. 553,971.

This invention relates to a type ejector for use in connection with a type setting or composing machine, which selectively feeds individual type through a common channel to an ejector. My improved type ejector is arranged to eject individual type from the discharge channel of the composing machine, in line formation, onto a suitable chase for printing purposes. This, therefore, is the general object of the present invention.

A further object of the invention is to provide a device which will, without clogging the channels or breaking type, receive and eject small individual type, such as is commonly used on the multigraph, at a rate of speed which is in excess of the rate of speed which an operator uses to select the type from a composing machine having a standard keyboard operating mechanism, whereby a very rapid operation of the machine may be obtained.

Other objects of this invention will become apparent from the following description, referring to a preferred embodiment thereof illustrated in the drawings. The essential and novel characteristics will be set forth in the claims.

In the drawings, Fig. 1 is an elevation of my improved type ejecting mechanism; Fig. 2 is a fragmentary vertical section through the ejector mechanism, as indicated by the line 2-2 on Fig. 1; Fig. 3 is a vertical transverse section as indicated by the line 3-3 in Fig. 2; Fig. 4 is a section taken in a plane substantially the same as Fig. 3, illustrating certain of the parts in a different position; Fig. 5 is a substantially horizontal section, as indicated by the line 5-5 of Figs. 1 and 4; Fig. 6 is a perspective view on a greatly enlarged scale, of a type, such as is commonly used in a multigraph, and for which type my ejector is especially designed.

The drawings illustrate a type ejecting mechanism, arranged to receive type from the discharge channel of a type setting or composing machine equipped with a keyboard to select the individual type and discharge them into a common delivery channel. I prefer this delivery channel to be substantially vertical, to enable the type to descend therein by

gravitation. At the base of this channel, I locate my improved type ejector, which is arranged to shove the type from the vertical channel laterally onto a suitable type chase.

The type chase may readily be a grooved segment, such as is commonly used on the multigraph. The segment is, of course, preferably removable from the type ejector mechanism so that it may readily be installed on the multigraph for printing purposes. The arrangement of my type ejector is such that it will discharge or eject type from the receiving channel at a much higher rate of speed than is possible for the operator to select individual type, with the usual keyboard operated type composing machine, and therefore prevents transposition of the type.

Referring again to the drawings, I show a preferred form of my invention mounted on a suitable table or frame 10, and arranged to receive type from a receiving channel 11, which is connected to the composing machine in the usual manner. The ejector mechanism is arranged to shove the type laterally from the receiving channel 11 onto a grooved segment or chase 14. The individual type may be supplied to a receiving channel 11, by a keyboard operated composing machine (not shown). The type, as they descend in the channel 11, which, at its lower end, is supported in a bracket 15, lie one on top of the other, coming to rest upon an ejector or plunger bar 16. The plunger 16 is mounted for reciprocation in a horizontally extending channel 18, in a base block 85

The channel 18 is arranged in a plane normal to the plane of the receiving channel 11. Hence, as the plunger moves to a point to the left of the channel 11, the type A', which rests on the upper face of the plunger (Fig. 3), will drop onto the bottom wall of the channel 18. Then, upon the forward movement of the plunger to the right-hand position, as shown in Fig. 3, the type A' will be shoved along the channel 18 into a suitable channel 19 of the type chase 14. The channels 19 are arranged in the usual manner so that they may be indexed and brought into alignment with the channel 18, as desired.

The operation is such that for each back 100

and forth movement of the plunger 16, the bottommost type in the channel 11 is shoved onto the chase. This operation is common to the action of many type ejectors. However, 5 until recently such type ejectors have been for the most part operated in a timed relationship to the operation of the composing machine.

Recently, keyboard controlled composing 10 machines have been built which are operated with comparatively little power and at a very rapid rate of speed, and it has become desirable to provide an ejector mechanism which will rapidly eject the type from the receiving 15 channel, so that the ejection will normally take place at a higher rate of speed than it is possible for an operator to operate the keys of the type setting machine, thereby preventing the type receiving channel from becoming 20 unduly filled, which would cause disadvantageous results. It is evident that with such composing machine, the type ejector must be constructed to eject type both when the channel contains many type or when a 25 type is dropped into the empty receiving channel without any regard whatsoever to the position of the type ejector plunger. This, of course, creates great possibilities for breakage and jamming of the type in the delivery channel.

To handle the type so as to avoid the possibility of breakage at the ejection region, I provide the controlling mechanisms now to be described. I arrange my type ejector so 35 that the type, as they descend through the channel 11, are stopped therein by a suitable mechanism and then permitted to drop one at a time before the withdrawn ejector bar 16, at a predetermined point in the travel of the 40 bar. This, therefore, prevents the type from being broken due to the differences between the timing of the operations of the type setting machine and the type ejector. To this end, I mount a plunger 20 in the rear or left- 45 hand face of wall of the receiving channel 11, and so arrange this plunger that it may be reciprocated by a bell crank 21, pivoted at 22 to the frame of the ejector, and resiliently urged into a position to cause the 50 plunger to be thrust into the channel 11 by a tension spring 23, secured at one end to an arm 24 of the bell crank 21, and at the other end to a suitable frame member 25. This arrangement is such that the plunger 20 is 55 normally in a position projecting into the channel 11 to prevent type lodged therein from descending into the channel 18.

To permit the type to fall in timed relationship relative to the plunger 16, I prefer 60 to provide the plunger with a pin or roller 27, which is arranged to coat with a cam surface 28 on a rearly extending arm 29 of the bell crank 21. When the plunger 16 is in its extreme right-hand position (Fig. 3), the 65 plunger 20 will be withdrawn from the chan-

nel permitting the type therein to descend, the bottommost type A' descending to a position where it rests on the top surface of the plunger 16.

Thereafter, as the ejector bar or plunger 16 is drawn to the left, from the position shown in Fig. 3, to that shown in Fig. 4, the plunger 20 is released, thereby permitting the spring 23 to force it against the second type from the bottom (namely, the type A' on 70 Fig. 3) and retain it in the channel 11, thereby permitting the bottom type A' to descend by gravity into a position resting on top of the plunger 16. As soon as the plunger 16 is completely withdrawn, the type A' will descend by gravity and rest before the plunger in the channel 18. Thereafter, the plunger is forced towards the right, ejecting the type 75 A out of the channel 18 and onto the type chase. 80

Due to the comparatively small size of the type and their irregular shape, they must be guided during the descending movement from the channel 11 into the channel 18. To this end, I so arrange the plunger 16 that it 85 is withdrawn only a comparatively slight distance to the left of the channel 11, and thereby enable the forward end thereof to form, when in the withdrawn position, a continuation of the rear wall 40 of the channel 11. At the right-hand end or outer face of the channel, I provide a guard in the way of a curved bar 30, having a beveled nose 31, arranged to operate in a slot 32 in the channel 11. The arrangement of this bar is such that when the plunger is in its extreme right or extended position, the nose of the bar extends into the channel adjacent the right-hand face of the type A, and as this type descends, due to the rearward movement of the bar, heretofore explained, the nose 31 of the lever 30, follows the type downwardly until it rests in the channel 16. This bar therefore forms a continuation of the front wall 41 of the channel 11, and, together with the front face of the plunger 16, prevents the type from turning or twisting in the channel 11, or by providing a restricted channel for the type. Likewise, when the plunger moves forward to eject a type, the pin 27 moves away from the cam surface 38, permitting the spring 35 to raise the guard and clear the path of the plunger 16.

To operate the type ejector, the plunger 16 is reciprocated. As shown in Fig. 1, a lever 50, pivoted at 51 to the frame 10, has a pin 55 and slot connection 52 with the plunger 16. On its lower end, the lever 50 carries a cam roller 53 arranged to be drawn into contact with a cam 54 by a suitable tension spring 55, one end of which is secured to a frame pin 56 and the other to the lower edge of the lever 50, as at 57. The cam 54 is rigidly secured to a shaft 58, journalled in the frame 10. A pulley 59 is rigidly secured to the shaft 58 and is driven, through the medium of a belt or chain 61 from a pulley 62, which is rigidly secured to the armature shaft 63 of a suitable motor 64. The arrangement is such that the ejector arm or plunger 16 is reciprocated at a much higher rate of speed than an experienced operator of type setting machine ordinarily operates the keys to select type therefrom.

From the foregoing description, it will be seen that I have provided a type ejecting mechanism, arranged to eject type laterally from a receiving channel onto a chase, wherein the type may descend in the channel either at a higher or a lower rate of speed than that of the ejector operation, without danger of damaging the type or ejecting mechanism and thereby prevent errors of transposition and the like, and eliminate the necessity of co-ordinated operating mechanisms in the composing machine and the type ejector or line-forming mechanism.

The prevention of breakage is of particular importance with the comparatively small type for which my ejector is especially designed, the size of the type having been exaggerated in the drawings, and especially in Fig. 6, to more clearly illustrate the invention. It will likewise be noted that the type A, for which my ejector is designed, are irregular in cross-section, having grooves "a" in the sides thereof, and the base "b" is narrower than the head "c". This presents a type which is readily broken and is easily turned and twisted in a comparatively small space. Hence, these type must be guided substantially throughout their entire progress in the various type channels of the ejecting mechanism. This, therefore, has presented a different problem of type ejection than was found in connection with composing machines in general.

I claim:

1. In the combination, with a channel for the descent of type, of means for laterally ejecting type from the channel, a laterally extending channel through which the type

are shoved by ejecting means, means arranged to enter the first-named channel to restrain the downward movement of type therein, said restraining means being operated in synchronism with the ejecting means to permit the type to descend one at a time on top of the ejecting means, and means to withdraw the ejecting means and cause the type resting thereon to drop into the last-named channel, whereby the next movement of the ejecting means will cause the type to be progressed along such channel.

2. In combination with a channel arranged to contain individual type, means for laterally ejecting type from the channel, a laterally extending guideway through which the type are shoved by the ejecting means, means arranged to restrain the downward movement of the type in the channel, and means operated by said ejecting means to operate the restraining means to relieve the restrained type one at a time and permit them to descend onto the ejecting means, and means to withdraw the ejecting means and thereby permit the type resting thereon to drop into the guideway.

3. In combination with a substantially vertical channel, arranged to guide descending type, a laterally extending guideway at the base of the channel and communicating therewith, a plunger reciprocably mounted in the guideway and arranged to support the bottommost type in the channel, a second plunger arranged to enter the channel and arrest the movement of second type above the first-named plunger, means to withdraw the first-named plunger and thereby permit the type thereon to descend into the guideway in front of the plunger, and means associated with said first-named plunger to withdraw the second-named plunger, permitting the type to descend and rest on the first-named plunger only when the latter is in its extended position.

4. In combination with a channel arranged to contain individual type, a plunger for laterally ejecting type from the channel and arranged to have a type descend onto it, a laterally extending guideway through which the type may be shoved by the ejecting means, means to withdraw the ejecting means and permit the type resting thereon to drop into the guideway in front thereof, and a guard arranged to enter said guideway to prevent the type which is descending from the top of the ejecting means from twisting during its descent to the guideway.

5. In combination with a channel arranged to contain individual type, means for laterally ejecting type from the channel, a laterally extending guideway through which the type are shoved by the ejecting means, means arranged to restrain the downward movement of the type in the channel,

- and means operated in synchronism with said ejecting means to withdraw the restraining means to permit the type to descend one at a time onto the ejecting means, means to withdraw the ejecting means and thereby permit the type resting thereon to drop into the guideway, and a guard arranged to enter said guideway to prevent the type which is descending from the top of the ejecting means 10 from twisting during its descent to the guideway.
6. In combination with a channel, arranged to guide descending type, a laterally extending guideway at the base of the channel communicating therewith, means to form a four-walled chamber at the lower end of the guideway arranged to receive a single type, said means comprising opposite walls of the guideway, the end surface of a plunger reciprocably mounted in the guideway, and a movable wall, means to withdraw the movable wall to permit the plunger to eject type from the chamber through the guideway.
7. In combination with a channel, arranged to guide descending type, a laterally extending guideway at the base of the channel, a plunger reciprocably mounted in the guideway and arranged to support the bottommost type in the channel, a means arranged to enter the channel and arrest the movement of second type above said plunger, means to withdraw the plunger and permit the type thereon to descend into the guideway in front of the plunger, and means associated with said plunger to withdraw the arresting means, permitting the type to descend and rest on the plunger, a movable guide member arranged to provide a continuation of one wall of the channel into the guideway, and means to remove said guide member from the guideway as the plunger is operated to eject the type therefrom.
8. In combination with a channel arranged to guide descending type, a laterally extending guideway at the base of the channel communicating therewith, a plunger reciprocably mounted in the guideway, a restraining device acting on type in the channel, a movable member acting on type in the guide- 50 way, means for operating the plunger, and means operated by the plunger for withdrawing the restraining device on one stroke of the plunger and for withdrawing said movable member on the opposite stroke of the plunger.
9. In combination, with a channel for the descent of type, of means for laterally ejecting type from the channel, a laterally extending channel through which the type are shoved by ejecting means, means arranged to enter the first-named channel to restrain the downward movement of type therein, and a lever for operating the restraining means having an inclined surface against which a projection on the ejector acts to withdraw the restraining means when the ejecting means moves to eject the type.
10. In combination with a channel, arranged to guide descending type, a laterally extending guideway at the base of the channel communicating therewith, a plunger reciprocably mounted in the guideway, and a movable wall carried by a lever having an inclined surface and a projection on the plunger adapted to engage said inclined surface when the plunger is moving to its inactive position.
11. In combination with a substantially vertical channel, arranged to guide descending type, a laterally extending guideway at the base of the channel and communicating therewith, a plunger reciprocably mounted in the guideway and arranged to support the bottommost type in the channel, a second plunger arranged to enter the channel and arrest the movement of second type above the first-named plunger, means to withdraw the first-named plunger and permit the type thereon to descend into the guideway in front of the plunger, a movable guide member arranged to provide a surface extending into the guideway in front of the type, and means to withdraw said guide member from the guideway, said two withdrawing means being directly operated by the first-mentioned plunger on its opposite strokes respectively.
- In testimony whereof, I hereunto affix my signature.

AUGUST L. SCHULTZ.
